RECORDED
UNITED STATES PATENT OFFICE.

ERASTUS E. WINKLEY, OF LYNN, MASSACHUSETTS.

SOLE-LEVELING MACHINE.

No 848,713.

Specification of Letters Patent.

Patented April 2, 1907.

Application filed April 2, 1903. Serial No. 150,704.

To all whom it may concern:

Be it known that I, ERASTUS E. WINKLEY, a citizen of the United States, residing at Lynn, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The present invention relates to sole-leveling machines, and more particularly to that class of sole-leveling machines which comprise a leveling-roll, a shoe-supporting jack, and mechanism for relatively actuating the jack and roll to level the sole of a shoe.

The invention is intended primarily as an improvement upon the sole-leveling machine disclosed in my prior patent, No. 555,548, dated March 3, 1896, although it is not limited to such machine, but may be embodied in other sole-leveling machines of the class above referred to.

In the machine disclosed in my prior patent the leveling-roll and shoe-supporting jack are so actuated that the two edges of the shank portion of the sole of a shoe are leveled successively, the edge which is first acted upon by the leveling-roll being determined by the shape of the operating-cams. By some shoe manufacturers it is considered preferable to have the leveling-roll act first upon the inner edge of the shank portion of the sole of the shoe, while other manufacturers consider it preferable to have the leveling-roll act first upon the outer edge, so that there is a demand for both types of machines.

The object of the present invention is to provide a sole-leveling machine in which the jack and roll can be so actuated as to cause the leveling-roll to act first upon either edge of the shank portion of the sole of a shoe, as may be desired.

In the machine illustrated in my prior patent above referred to the shape of the operating-cams and the connections between the cams and the jack and leveling-roll are such that when the cam-shaft upon which the cams are mounted is rotated in one direction the leveling-roll is caused to act first upon the inner edge of the shank portion of the sole of the shoe being operated upon and when the cam-shaft is rotated in the oppo-

site direction the leveling-roll is caused to act first upon the outer edge of the shank portion of the sole. In order to allow the cam-shaft of this machine or the shaft of any sole-leveling machine, comprising a leveling-roll, a shoe-supporting jack, a shaft, and suitable connections for relatively actuating the roll and jack, to be rotated in either direction, so as to cause the leveling-roll to act first either upon the inner or the outer edge of the shank portion of the sole of the shoe as desired, my invention contemplates providing means for automatically stopping the rotation of the shaft at the completion of the sole-leveling operation when the shaft is rotated in either direction.

My invention also contemplates providing means for disconnecting the jack from the shaft at the proper time during the operation of the machine when the shaft is rotated in either direction, this feature of my invention being particularly applicable to a sole-leveling machine in which two or more jacks are provided and a common actuating mechanism therefor, as in the machine of my prior patent.

In addition to the features of invention above referred to my invention also consists in the arrangements and combinations of parts hereinafter described and claimed, the advantages of which will be obvious to those skilled in the art.

A preferred form of my invention is illustrated in the accompanying drawings, in which—

Figure 1 is a view in side elevation of so much of the sole-leveling machine disclosed in my prior patent, No. 555,548, as is necessary to show the connection of the invention therewith, certain parts of the machine being broken away to show underlying parts. Fig. 2 is a detail plan view illustrating the mechanism for stopping the rotation of the cam-shaft at the end of the sole-leveling operation when the cam-shaft is rotated in either direction. Fig. 3 is a detail sectional view illustrating the mechanism by which the jacks are disconnected from the cam-shaft, and Fig. 4 is a detail perspective view illustrating the double-pointed cam which forms a part of the mechanism for disconnecting the jacks from the cam-shaft.

The sole-leveling machine illustrated in the drawings, except for the parts hereinafter specifically described as the illustrated em-

bodiment of the present invention, is the same in all essential particulars as the machine disclosed in my prior patent, comprising two pivotally-mounted jacks, two coöperating vibrating leveling-rolls, a cam-shaft, and suitable connections for oscillating the jacks and tipping the rolls, and locking devices for locking either jack to the connections by which it is operated from the cam-shaft.

A full disclosure of the construction and mode of operation of the parts above referred to being contained in my prior patent, further description and illustration thereof in this application is considered unnecessary.

The mechanism for driving the cam-shaft is the same as in the machine of my prior patent and comprises a driving-shaft 1, worm-gears 2 and 3, a shaft 4, upon which 20 the worm-gear 3 is mounted to rotate loosely, a clutch 5 for clutching the worm-gear 3 to the shaft 4, a worm 6 upon the shaft 4, and a worm-gear 7, secured to the cam-shaft and meshing with the worm 6. The shipper-rod 25 8 for actuating the clutch 5 to connect and disconnect the worm-gear 3 and shaft 4 is also the same as in the machine of my prior patent.

In carrying out my present invention I 30 have provided a sleeve 9, mounted to slide longitudinally on the shipper-rod. From this sleeve an arm 10 projects into the path of movement of a projection 11, secured to the worm-gear 7 or to one of the cams upon 35 the cam-shaft, the arrangement being such that the engagement of the projection 11 with the arm 10 when the cam-shaft is rotated in either direction moves the sleeve 9 longitudinally in one direction or the other, 40 depending upon the direction in which the cam-shaft is rotated. The longitudinal movement of the sleeve 9 in either direction is utilized to move the shipper-rod 8 in a direction to disengage the clutch 5 from the worm-gear 3, and thus stop the rotation of the shaft 4. When the sleeve 9 is moved to the 45 left as viewed in Figs. 1 and 2, the shipper-rod 8 is also moved to the left by the engagement of the sleeve with a collar 12, secured to the rod. In order to cause the rod 8 to be moved to the left when the sleeve 9 is moved to the right as viewed in Figs. 1 and 50 2, a rod 13, mounted to slide in arms 14, secured to the shipper-rod 8, is provided, one end of which is engaged by an arm 15, projecting from the sleeve 9, and the other end of which is arranged to engage the upturned end of one arm of a lever 16, the other arm of which bears against an arm 17, secured to the rod 8.

By means of the construction so far described the cam-shaft is automatically stopped at the completion of the sole-leveling operation, when the shaft is rotated in either direction. In order to start the cam-shaft into

operation, a treadle 18, secured to the shipper-rod 8, is provided, as in the machine of my prior patent. The depression of this treadle rocks the shipper-rod 8 and sleeve 9, so as to remove the arm 10 from engagement 70 with the projection 11. As soon as the arm 10 is disconnected from the projection 11 the shipper-rod 8 is moved to the right, so as to bring the clutch 5 into engagement with the worm-gear 3 by a spring 19, coiled around the 75 rod and interposed between the frame of the machine and the collar 12. The shipper-rod 8 and sleeve 9 are rocked in the opposite direction to again bring the arm 10 into the path of movement of the projection 11 as 80 soon as the treadle 18 is released by means of a coiled spring 20, connecting the upper end of the arm 17 and the frame of the machine. The rocking movement of the rod 8 and sleeve 9 under the force of the spring 20 is 85 limited by a stop-arm 21, projecting from the hub of the arm 17 beneath a fixed portion of the machine-frame, as is clearly shown in Fig. 2. In order to cause the sleeve 9 to be rocked with the rod 8, the sleeve is provided 90 with a pin 22, which engages a slot in an arm projecting from the collar 12.

In connection with the mechanism above described for automatically stopping the cam-shaft when rotated in either direction the machine illustrated in the drawings is provided with means for disconnecting the jack which is being operated from the cam-shaft at the end of the sole-leveling operation. This means, as illustrated, consists of a double-pointed cam-projection 23, secured to the periphery of one of the cam-disks on the cam-shaft, which cam-projection is arranged to actuate the pawls 24 during the last portion of the revolution of the cam-shaft, so as to move the spring-pressed locking-pins 25 inwardly and disconnect the jack which has last been operated. The cam-projection 23, the pawls 24, and the locking-pins 25 are constructed and arranged to operate as fully 100 illustrated and described in the patent to Winkley and Phillips, No. 540,223, dated May 28, 1895, with the exception that the cam-projection 23 is double-pointed and is thus adapted to actuate the pawls when the 105 shaft rotates in either direction. It is desirable that the cam-projection 23 should pass beyond the pawls 24 before the rotation of the cam-shaft is stopped in order to allow a jack to be connected to the actuating mechanism before the cam-shaft is again connected to its driving mechanism. To secure this result when the cam-shaft rotates in either direction, I have provided means for relatively adjusting the cam-projection 23 and the projection 11 circumferentially of the cam-shaft. As shown in the drawings, this relative adjustment is secured by adjusting the cam-projection 23, which is adjustably 110 secured to the periphery of one of the cam- 115

disks on the cam-shaft by means of bolts 25^a, passing through slots in a plate 26, formed integral with or secured to the projection 23.

Having thus indicated the nature and scope 5 of my invention and having specifically described a construction embodying a preferred form thereof, I claim as new and desire to secure by Letters Patent of the United States--

1. A sole-leveling machine, having, in 10 combination, a leveling-roll, a shoe-supporting jack, a shaft and suitable connections for relatively actuating the jack and roll to level the sole of a shoe supported upon the jack, and mechanism acting automatically to stop 15 the rotation of the shaft when the shaft is rotated in either direction, substantially as described.

2. A sole-leveling machine, having, in 20 combination, a leveling-roll, a shoe-supporting jack, a shaft and suitable connections for relatively actuating the jack and roll to level the sole of a shoe supported upon the jack, and mechanism acting automatically to disconnect the jack from the shaft when the 25 shaft is rotated in either direction, substantially as described.

3. A sole-leveling machine, having, in 30 combination, a leveling-roll, a shoe-supporting jack, a shaft and suitable connections for relatively actuating the jack and roll to level the sole of a shoe supported upon the jack, driving mechanism for the shaft including a clutch, a projection mounted to move with the shaft, an arm arranged to be engaged by 35 said projection when the shaft is rotated in either direction and to be moved in opposite directions thereby, and connections between said arm and said clutch for actuating the clutch to stop the rotation of the shaft when 40 said arm is moved in either direction, substantially as described.

4. A sole-leveling machine, having, in 45 combination, a leveling-roll, a shoe-supporting jack, a shaft and suitable connections for relatively actuating the jack and roll to level the sole of a shoe supported upon the jack, driving mechanism for the shaft including a clutch, a projection mounted to move with the shaft, an arm arranged to be engaged 50 by said projection when the shaft is rotated in either direction, connections between said arm and said clutch for actuating the clutch to stop the rotation of the shaft, and means for disconnecting the jack from the shaft including a cam projection mounted to move with the shaft, and adjustable circumferentially thereof, substantially as described.

5. A sole-leveling machine, having, in 55 combination, a leveling-roll, a shoe-support-

ing jack, a shaft and suitable connections for 60 relatively actuating the jack and roll to level the sole of a shoe supported upon the jack, driving mechanism for the shaft including a clutch, a projection mounted to move with the shaft, an arm arranged to be engaged by 65 said projection when the shaft is rotated in either direction, connections between said arm and said clutch for actuating the clutch to stop the rotation of the shaft, and means for disconnecting the jack from the shaft including a cam projection mounted to move with the shaft, said projections being relatively adjustable circumferentially of the shaft, substantially as described.

6. A sole-leveling machine, having, in 70 combination, a plurality of shoe-supporting jacks, a plurality of leveling-rolls, a shaft and suitable connections for relatively actuating each jack and its coöperating roll to level the sole of a shoe, driving mechanism for the 75 shaft including a clutch, a projection mounted to move with the shaft, an arm arranged to be engaged by said projection when the shaft is rotated in either direction, connections between said arm and said clutch for 80 actuating the clutch to stop the rotation of the shaft, and means for disconnecting each jack from the shaft including a cam projection mounted to move with the shaft, said projections being relatively adjustable circumferentially of the shaft, substantially as 85 described.

7. A sole-leveling machine, having, in 90 combination, a plurality of shoe-supporting jacks, a plurality of leveling-rolls, a shaft and suitable connections for relatively actuating each jack and its coöperating roll to level the sole of a shoe, and mechanism acting automatically to disconnect each jack from the shaft when the shaft is rotated in either 95 direction, substantially as described.

8. A sole-leveling machine, having, in 100 combination, a leveling-roll, a shoe-supporting jack, a shaft and suitable connections for relatively actuating the jack and roll to level the sole of a shoe supported upon the jack, and mechanism acting automatically to disconnect the jack from the shaft when the shaft is rotated in either direction and to stop 105 the rotation of the shaft, substantially as described.

In testimony whereof I affix my signature in presence of two witnesses.
